UNITED STATES PATENT OFFICE.

JONATHAN LUCAS, OF NEW YORK, N. Y., ASSIGNOR TO LUCAS-LAMBORN LOOM CORPORATION, OF NEW YORK, N. Y., A CORPORATION OF NEW YORK.

BOBBIN-FEEDING MECHANISM FOR LOOMS.

Application filed December 27, 1922. Serial No. 609,274.

This invention relates to improvements in looms.

The object of the invention is to provide an improved form of bobbin feeding mechanism which is certain and entirely automatic in operation.

It is also an object of the invention that the bobbin feeding mechanism be adapted to thread the shuttle simultaneously with the feeding of a bobbin thereto so that every movement of the shuttle is utilized for placing filling threads between the warp threads.

A still further object of the invention is that the bobbin supporting means of the shuttle together with the means for feeding the yarn or thread from the bobbin be adapted to utilize the so-called universal winding of spool or bobbin.

It is also an important object of the invention that the yarn or thread feeding means from the bobbin carried by the shuttle eliminate any possibility of breaking a thread of yarn of any strength.

Other objects, and objects relating to details of construction, combination and arrangement of parts will hereinafter appear in the detailed description to follow.

The invention is illustrated by way of example in the accompanying drawings, in which:

Figure 1 is a view in front elevation of the parts of a loom embodying the present invention.

Figure 2 is a fragmentary view in front elevation showing the portion of loom in which my invention relating to the shuttle feeding mechanism is incorporated.

Figure 3 is a top plan view of the same.

Figure 4 is a vertical transverse sectional view taken substantially on the line 4—4 of Figure 1.

Figure 5 is a detailed sectional view taken substantially on the line 5—5 of Figure 4.

Figure 6 is a top plan view of the shuttle with the casing thereof removed.

Figure 7 is a view in side elevation of the same showing the casing applied in dotted lines.

Figure 8 is a perspective view of a bobbin illustrating the particular winding thereof and also showing connected thereto the necessary weft weight.

Figure 9 is a vertical sectional view through a bobbin and particularly illus-

trating the manner in which the spool may be connected thereto.

Figure 10 is a detailed perspective view of the actuating elements associated immediately with the power shaft and showing the 60 harness connected therewith.

Figure 11 is a longitudinal sectional view of shuttle.

Like reference numerals refer to similar parts throughout the several views.

The means for operating the shuttle, that is, passing the same to and fro through the warp threads will be first described. This arrangement is substantially shown in my co-pending application Serial No. 536,258, 70 filed Feb. 13, 1922.

In the drawings B indicates generally a base which is elongated, as shown, and at each end there is formed an upright or post P and P¹ respectively, the post P¹ being 75 the greatest in height as shown. Intermediate the posts P and P¹ there are located the two posts P² which extend upwardly from the base B and may be formed integrally therewith as shown. The base is 80 preferably of the width shown in Figure 4; and at its longitudinal center and adjacent the outer side thereof there extends upwardly a pair of posts P³. Also in alignment with these posts there is formed a 85 third post P⁴. A shaft S² is journaled on the posts P³ and P⁴, said shaft carrying a cog wheel 10 at a point adjacent the innermost post P³, and said cog wheel being in constant mesh with a pinion 11 carried by 90 a crank shaft generally indicated at C, said crank shaft being journaled on the pair of posts P³ and carrying upon its outer end a pulley 12 over which there passes a belt 13 which is driven from the motor M. The 95 pinion 11 is in constant mesh with a cog wheel 14, said cog wheel in turn being secured to a shaft 15 which is journaled upon the upper ends of the posts P³.

The crank shaft C is formed with two 100 crank arms or portions which are disposed at 180° with respect to each other, and to each crank portion there is connected the inner end of a connecting bar 16. From each post P and P¹ there is extended an arm 105 17 to which in each instance there is fulcrumed a lever bar 18, said lever bar being fulcrumed at a point adjacent its one end, as shown, and having its lower end pivotally connected to the outer end of the 110

associated connecting bar 16. The purpose of the lever bars 18 will later become apparent.

Each post P and P¹ is also formed with a bracket arm 19 extending from the inner side thereof to which there is fulcrumed in each instance a bell crank lever 20. Each bell crank lever 20 has one arm pivotally connected to a connecting bar 21, said connecting bars 21 being connected at their other ends to a crank arm carried by the cog wheel 14 as at 22, Figure 4.

Each post P and P¹ carries a slide box 23, said slide boxes occurring adjacent the upper ends of the post upon the inner sides thereof and being in alignment. Within each slide box there is slidably positioned a bar 24 which carries a stop-member 25 adjacent its lower end, said stop-member being adapted to move in a slot of the boxing in each instance, said slot extending longitudinally of each boxing as at 26, Figure 4. The lower end of each bar 24 is connected to the free arm of the associated bell crank lever 20 through the means of a link 27. The upper end of each bar 24 also carries a stop as at 28 which has its upper surface inclined as shown.

Through each post P and P¹ there is slidably extended a shuttle carrier rod generally indicated by the reference character R. Each rod is formed at its outer end with a slotted enlargement as at 29, Figure 1, through which the upper end of the associated lever bar 18 extends. The inner end of each rod R terminates in an enlargement 31 which is substantially rectangular in shape and from each side thereof projects a finger 32, Figures 1 and 3, said fingers extending parallel to each other, as best shown in Figure 3, and projecting from the enlargement 31 substantially the distance shown. Each enlargement 31 is provided with a vertical slot through which there is extended and fulcrumed a latch supporting member 34. Each latch supporting member terminates at its lower end in a protrusion 35 which extends toward the associated slide 23. The upper end of each member 34 pivotally supports a latch member generally indicated by the reference numeral 36 which consists in a short bar section terminating at its inner end in a downwardly extending protrusion 37. The latch members 36 are spring controlled and adapted to be either brought to maintain a horizontal position or the tilted and inclined position illustrated in Figure 1 of the drawings.

The shuttle generally indicated by the reference character S may consist in a frame F rectangular in shape and best shown in Figure 6, and upon this frame there is positioned a cap or a cover 38, Figures 3 and 7, and within this frame the mechanism for supporting the bobbin and

discharging the spool or exhausted bobbin is supported. This construction will be later described. The frame F has each side member formed with a pair of lips 39 to provide in each instance a groove or channel 40 adapted for receiving the fingers 32 of the shuttle carrying rods R. The channels or grooves 40 formed by the lips 39 are each disposed in the same horizontal plane, and the channel in each instance is closed at its one end as at 41, said closure forming a sloping wall as best illustrated in Figure 7. The fingers 32 of the shuttle carrying rod occurring upon the left hand side of the loom are adapted to pass within the channels or grooves 40, while the fingers 32 projecting from the shuttle carrying rod R occurring upon the right hand of the loom are adapted to slide beneath the lowermost lip 39 and in this way support the shuttle. Also it should be mentioned that the fingers of each shuttle carrying rod are adapted to support the shuttle in the same plane at all times.

The frame F of the shuttle carries at each end a hook 42 which is adapted to be engaged by the protrusion 37 of the latch members 36. The reciprocation of the shuttle may take place in the following manner: The motor M may be started to rotate the shaft S² which will in turn in an apparent manner operate the bell cranks 20 for reciprocating the bars 24 inversely. The connecting bars 16 will also reciprocate the shuttle carrying rods R inversely. Assume that the shuttle is in the position, shown in Figure 1, that is, released from its associated latch 36 due to the lower end of the latch engaging with the stop member 25 and thus raising the said latch from the hook 42 of the shuttle. Now upon the shuttle carrying rods R moving toward each other, and as the fingers carried by the rod R on the left hand side of the loom proceed into the grooves 40 of the shuttle casing, the latch 36 associated with this rod will engage with the hook 42 occurring at this end of the shuttle, and upon the rods moving in the opposite direction, the shuttle will be transferred from the rod upon which it was disposed or carried to the other rod. Upon the rods reaching their extreme outward movement the latch 36 on the rod carrying the shuttle will engage with the stop member 25 and release the same while the latch carrying element 34 of the other rod R will be engaged by the stop 28 and the associated latch and swing to its horizontal position. Now the shuttle carrying rods will again move toward each other and in this way the shuttle will be again transferred and moved to its other extreme position. In this manner the continuous reciprocation or passing to and fro of the shuttle through the feed of the warp threads is effected.

The shuttle S is shown in detail in Figures 3, 6 and 7 of the drawings. The frame F, cap 38 and hooks 42 of the shuttle have heretofore been referred to. Between the two side members of the frame F there is journaled a pair of shafts 43 and 44; a shaft occurring adjacent each end of the frame. The shafts may be rotatably supported by L-shaped clips as at 45^a. Each shaft 43 and 10 44 supports a rocker frame F¹, each frame consisting in a rectangular loop of wire 45 secured to the associated shaft 43 or 44 at a point off-center with respect to the length of each frame, and thus in each instance, 15 disposing the greater portion of the frame F¹ upon the inner side of the supporting shaft. The outer side member 46 of each frame F¹ is enlarged to give sufficient weight so that the frames F¹ will be normally disposed in a substantial horizontal plane with the enlarged side portions thereof resting upon the ends of the shuttle frame F. The frame F¹ carried by the shaft 43 is provided with a longitudinal brace 47, 20 and this same portion of the frame adjacent its inner end carries a downwardly disposed U-shaped portion 48 which extends longitudinally of the frame, as shown in Figure 6. This depending U-shaped portion is adapted to move upon the inner side of the rod 49 when the frame tilts inwardly, and the rod 49 limits the downward movement of the frame. The inward tilting movement of the frame associated with 25 the rod or shaft 44 is limited by a rod 50. Forward of the rod 49 there is positioned a rod 51 which is in a plane slightly below the rod 49 so that it will not interfere with the downward tilting movement with the inner side of the frame carried by the shaft 43. A frame F² is rockably mounted beneath the inner side of the frame carried by the rod 44. The frame F² is rectangular in shape and its end portions 53 supported 30 off-center by suitable studs 54 extending from the sides of the shuttle frame F. The outer side portion of the frame F² carries a weight 55 which tilts the inner side of the frame upwardly and against the rod 50^a when the shuttle is empty. 35 The shaft 44 has its one end extended into a crank arm 56, said crank arm terminating in a flat head 57. One of the side members of the shuttle frame F has its top surface at a point adjacent its inner edge and at its longitudinal center provided with a recess 58 which is preferably of the shape shown, and upon each side of this recess there is secured to the same member of the frame a clip 59, said clip in each instance consisting in a bracket portion by which the same may be secured to the frame F and a plate portion 60 which extends parallel with the inner side of the associated 40 side member of the frame F. The oppos-

ing ends of the plate portions 60 are in spaced relation to provide a guideway, the purpose of which will later be explained. The other side member of the shuttle frame F is also formed with a recess 61 which is 70 larger than the recess 58 and forms a curved wall as shown, both recesses serving to make the parts carried by the shuttle readily accessible.

To the side of the shuttle frame F having 75 the recess 61 there is secured a bracket 62. This bracket has its supporting portion 63 extending vertically and bifurcated whereby to pivot the one end of a finger 64 by means of a pin, or the like 65. The finger 64 terminates at its free end in a curved portion 66, and said finger may be disposed between a pair of guide plates 67 extending from the portion 63 of the bracket 62, and said guide plates each terminating in a curved portion 68. The finger 64 is free to be swung upwardly and rearwardly with respect to the shuttle and said spring finger carries a spring wire 69 which has its one end secured to a point adjacent the pivotal point 90 of the finger 66 and its free end slightly raised with respect to the upper end of the finger 64 as illustrated in Figure 7. The portion 63 of the bracket 62, as before stated, is bifurcated and each of the upper edges so formed is provided with a notch 95 69, which notches are in alignment with each other, and the portions 70 of the upper edges of said bracket portion 63 are of less height than the remaining portions, and these portions 70 have their upper edges arcuate in shape as shown.

The bracket plate portion 63 also fulcrums a lever bar generally indicated by the reference numeral 63' which has its upper edge formed with a recess 64'. The lever is fulcrumed off-center so that its end portion 65' is normally below the other end portion of said lever as illustrated in Figure 7. 110

In order to supply a number of bobbins of yarn or thread to the shuttle there is provided a magazine generally indicated by the reference character M¹ which is vertically arranged and which may be made of any height to support the number of bobbins desired. This magazine is supported by the longitudinal frame members 71 which extend forwardly from the post P¹. From each longitudinal frame member 71 occurring on the one side of the post there is extended an auxiliary supporting frame member 71', and between the free ends of these members there is supported the magazine M¹, said magazine consisting in a plurality of slats 72 arranged in spaced relation and adapted to receive therein a block or weight 73. 115 120 125

The magazine M¹ consists in a sheet metal or other suitable material and having 130

a longitudinally extending slot as at 74, Figures 3 and 4, through which the yarn or thread from the bobbin may pass. Also the outer wall of the magazine may carry at 5 its edge associated with the slot 74 a wire frame 75, said frame having its vertical portion extending parallel with the slot 74 but disposed forwardly thereto. The magazine M^1 is also formed with a longitudinally 10 extending slot 76 through which the yarn may pass as illustrated in Figure 3. This slot is closed at its lower end. The yarn or thread is indicated by the reference numeral 77 and shown as having its free 15 end secured to the weight 73 which is in the magazine M^1 . The bobbin is generally indicated by the reference character B^3 and specifically shown in Figure 8 of the drawings.

20 The cap 38 of the shuttle S is provided with an opening 38' through which the bobbin B^3 may be inserted. Also one side wall of the cap is provided with a vertical slot 36', the purpose of which will later be made 25 apparent. The thread or yarn extending from this bobbin, as shown, is tied to a block of wood which represents the weight before referred to. This block of wood should have a narrow groove formed about 30 the same at a point intermediate its ends as at 79 into which the yarn or thread may be wound and thus to secure the thread to the block of wood or weight. This weight or block of wood is of such dimensions that 35 it may easily pass downward through the magazine M^1 when disposed longitudinally with relation to the magazine.

Between the magazine M^1 and post P^1 there is extended a pair of supporting bars 40 80. Above each bar 80 there is also extended between the magazine M^1 and post P^1 a bar 81, said bars in each instance having formed intermediate their ends an up-standing post 82. Each post 82 is provided 45 with an opening through which there slidably passes a rod 83. The rods 83 are connected by the rod 84 which has its one end extended in a portion 85, said portion terminating in a portion 86 which is parallel 50 with the frame members 71'. The free end of the rod extension 86 is slidable through a bracket 87 secured to the magazine M^1 and also slidable into the magazine M^1 through a suitable opening formed in the 55 side of said magazine. Preferably this rod is pointed at its free end.

The members 80 are relatively close to each other and between these members there is fulcrumed a lever bar 88 by the means 60 of a pin 89. Each end of this bar is bifurcated as best shown in Figure 2 and the upper end of the lever engages the rod 85. The rods 83 both enter the magazine M^1 through suitable openings provided in the 65 adjacent wall of the magazine. Beneath

the bars 80 there is extended from the post P^1 a pair of bars 90, each bar carrying a pair of upright apertured posts 91. The post 91 of each bar 90 slidably supports a rod 92 which extend into the magazine M^1 70 at their one end. The rods 92 are connected by a rod 93 and said rod 93 is engaged by the lower and bifurcated end of the lever bar 88. The rod 93 is extended from its one side end to terminate in a rod portion 94 which is parallel with the extension 86 of the rod 85 and which extends into the magazine M^1 and supported by a bracket 94'. To the upper end of the lever bar 88 there is pivotally connected the one end of 80 a connecting bar 95 as at 96, said bar being pivotally connected at its other end to a lever bar 97, said lever bar 97 having its other end rigidly secured to a transverse shaft 85 which terminates at its one end in a crank arm 94'. The last named end of the connecting bar 95 has attached thereto the one end of a coiled spring 98, said coiled spring having its other end attached to the post P , as shown in Figure 2.

The bobbin B^3 of the universal form of winding is well understood by those skilled in the art and so illustrated in Figure 8 of the drawings. The spindle S^1 consists in a wooden core carrying a pair of diametrically opposed spring fingers 100 which extend longitudinally of the core and are compressible. The yarn or thread forming the bobbin is wound upon a spool 101 which may be of card-board or the like and which is cylindrical in shape as shown. When the spindle S^1 is inserted in the spool the spring fingers 100 prevent accidental removal of the spool. One end of the spindle has threaded therein a screw 102. When placing a bobbin upon the shuttle the head of screw 102 is adapted to cooperate with the plate portion 60 of the clips 59 carried by the shuttle and holds the bobbin against movement in one direction in an obvious 105 manner.

The operation of the bobbin feeding mechanism heretofore described is as follows: Assuming that the shuttle is in one of its extreme positions, as illustrated in Figure 1 of the drawings, and thus brought directly beneath the magazine M^1 which is loaded with a number of bobbins B^3 as illustrated in Figure 2; also assuming that the bobbin within the shuttle has become exhausted, that is, the thread upon the bobbin, and upon this occurring the weighted sides of the frames F^1 will rock these frames so that they will assume a horizontal position and permit sufficient room for the passage of the spool 101 of the bobbin between their opposing sides and thus to drop the spool upon the inner side of the frame F^2 . The spool will be temporarily supported in this position. Now if this occurs immediately 115 120 125 130

- before the shuttle reached its last named extreme position, the crank shaft 44 has been rotated so as to lift its head 57 and likewise permit movement of the lever 63' before the shuttle reached its last named extreme position, the crank shaft 44 has been rotated so as to lift its head 57 and likewise permit movement of the lever 63' 5 to raise its end 65'. Heretofore the crank portion of the shaft 44 has engaged the lever 63' to hold it in the position illustrated in Figure 7 of the drawings. Upon the movement of the lever 63' its end 65' will be in a position to engage the crank arm 94' and as the movement of the shuttle toward its extreme position continues will swing the lever bar 97 inwardly against the tension of the spring 98 and thus to in turn move the rods 83 inwardly and the rods 92 outwardly, whereupon the lowermost bobbin B³ will be dropped from the magazine M¹ and another bobbin B³ be substituted in the magazine for the one dropping therefrom. 10 Upon the bobbin B³ coming from the magazine the same will drop through the opening 38' in the housing 38 of the shuttle S and fall upon the rocker frames F¹ and swing their inner sides downwardly. Also 15 the new bobbin coming upon the shuttle will cause the spool resting upon the inner side of the frame F² to drop therefrom, and this spool may roll into a container provided therefor. The head of screw 102 of the 20 spindle S¹ will be positioned between the plate portions 60 of the clips 59 and thus hold the bobbin against longitudinal movement in one direction. With the bobbin dropping the weight of block 73 secured to 25 the yarn on this bobbin will drop from the magazine M¹. This for the reason that the rod portions 86 and 94 entering the magazine M¹ will be simultaneously operated with the rods 83 and 92 to drop the weight 30 or block, and it is thought this operation is entirely apparent without further description. The thread or yarn between the bobbin and weight 73 will now cross the forward end of the finger 64. Assuming that 35 the shuttle now begins its movement toward its other extreme position the weight 73 causes the thread to be drawn beneath the spring 68 of the finger 64 and into the notches 69 and also drawn so that the thread 40 passes through the slot 36' in the one side of the shuttle housing 38. This operation may be repeated at each time that the bobbin becomes exhausted. 45 The present apparatus is shown as employing two sets of harness each generally indicated by the reference character H. For operating these harness the shaft S² carries a pair of cams 104, one for each of the harness H. Each of the cams 104 has a 50 working edge surface which is arcuate in shape and substantially equal to 180° and so arranged that said cams will alternately lift the two sets of harness H. Each set of harness consists in a frame 105 and within 55 each frame there is supported the usual heddle wires 106. The frame 105 in each instance is carried or supported by U-shaped frame 105' and this is carried by rods 107 which in turn are properly supported for vertical movement and which each carry at 60 their lower end a plate 108 which is bifurcated and straddles the shaft S². Each plate 108 carries a roller 109 which is adapted to engage the peripheral surface of the associated cam 104. 65 At B⁴ there is diagrammatically indicated the warp beam and at C³ is diagrammatically indicated a cloth roll, Figure 4. At 106^a and 107^a there is indicated the two sets of warp threads controlled by the two sets of harness H. The sets of warp threads 106^a and 107^a when held as illustrated in this figure provide the usual shed through which the shuttle S passes. 70 For the beater there is provided a frame F⁴ which is slidably supported for movement in a horizontal plane by guideways 109 which may be supported between the posts P² and also between extensions 110 from the posts P³, Figure 4. The beater frame F⁴ carries at its end adjacent the cloth roll C² an upright frame F⁵ in which there is provided the usual reed R³ through 75 which the warp threads pass. 80 The base B of the loom may have formed on its inner side an extended portion 111 which may be formed with an upright 112 terminating in an inwardly disposed arm 113. Also this extension 111 may be recessed as at 112'. A bell crank lever 113' is 85 fulcrumed by a pin 114, the fulcruming pin being disposed in the recess 112'. Each arm 115 and 116 of the bell crank lever has its end bifurcated as at 117. The arm 115 has 90 its end straddling a pin 118 carried by the lower end of the lever 119 fulcrumed to the arm 113 by a pin or the like as at 120. The upper end of the lever 119 is bifurcated as 95 at 121 and this end straddles a pin 122 carried by a lug 123 depending from the beater frame F⁴. The full lines of the lever 119 and bell crank lever 113 indicate the one 100 extreme position thereof, while the lines 124 and 125, respectively, indicate the other extreme position. The inner end of the shaft 105 S carries a cam 126 Figures 4 and 5, said cam having two swells 127 which are diametrically opposed to each other. Upon the inner side of the cam 126 there is positioned 105 a vertically movable frame 128 which may be U-shaped for straddling the shaft S and be supported by a U-shaped bracket member 129. The bridge portion of the frame 128 may be straddled by the bifurcated end of the crank lever arm 116. The frame 128 should carry a roller 130 which is adapted 110 to ride upon the peripheral surface of the cam 126 and thus to move the frame 128 upwardly and downwardly twice during one revolution of the cam. The guide plates 115 120 125 130

131 hold the roller 130 upon the peripheral surface of the cam as illustrated in Figure 10. With each vertical movement of the frame 128 the beater frame F⁴ will be moved 5 toward the cloth roll C³ and thus carry the reeds between the warp threads and pack the filler threads placed in position by the shuttle S.

The sets of harness H are operated in 10 synchronism with the beater frame F⁴ and likewise these two units function in synchronism with the shuttle S so that upon each passage of the shuttle between the warp threads 106^a and 107^a the harnesses are 15 moved to reverse the positions of these warp threads, and the beater frame F⁴ is moved to pack the filler thread or woof left by the shuttle. It is thought that with this explanation, the invention relating to the novel 20 form of beater and also novel means for operating the sets of harness H may be clearly understood without further detailed description. The operation of the bobbin feeding mechanism together with the operation of 25 the shuttle S has heretofore been given and it is believed that these operations taken with the operations of the beater and harness described is sufficient to give to those skilled in the art a clear and comprehensive 30 knowledge of the manner in which a loom constructed in accordance with our invention may operate.

While I have shown and described the preferred form of my invention, I wish it to 35 be understood, that the construction, combination and arrangement of parts may be changed by those skilled in the art without departing from the spirit of the invention, as indicated by the appended claims.

40 I claim:

1. In a bobbin feeding mechanism for looms, a bobbin magazine arranged to contain a supply of new bobbins, tripping

mechanism for holding said bobbins normally in the magazine, a shuttle having a 45 path of travel which extends into receiving relation to said magazine, supporting devices on said shuttle controlled by the supply of yarn on the bobbin in said shuttle and automatically adjustable to a position as the 50 yarn is used up, to permit the empty bobbin to drop in said shuttle, a yieldable device for receiving and holding the empty bobbin in its dropped position, and means adjusted by one of said supporting devices into position for actuating said tripping mechanism to release the terminal bobbin from said magazine and to permit it to drop into the shuttle and to push the empty bobbin from 55 said yieldable device.

2. In a bobbin feeding mechanism for looms, a bobbin magazine arranged to contain a supply of new bobbins, a tripping mechanism for normally holding said bobbins in said magazine, a shuttle having a 60 path of travel which extends into receiving relation to said magazines, rocker frames pivotally mounted in said shuttle and projecting towards each other for supporting a bobbin in said shuttle, means for automatically adjusting the frames to inoperative 65 position when the bobbin is empty to permit the empty bobbin to drop in said shuttle, a receiving frame pivotally mounted in said shuttle for yieldably supporting 70 the empty bobbin in its dropped position, a crank arm connected with one of said rocker arms, and a lever controlled by said crank arm and movable to a position to actuate said tripping mechanism when said rocker frames are adjusted to their inoperative 75 position whereby the terminal bobbin in said magazine is transferred to the shuttle and the empty bobbin is removed from said shuttle.

JONATHAN LUCAS.
